Des. 236,022

Patented July 22, 1975

236,022

CEILING LAMP

Lodovico Magistretti, Via Conservatorio 20, Milan, Italy

Filed Mar. 13, 1973, Ser. No. 340,785

Claims priority, application Italy Sept. 19, 1972

Term of patent 7 years

Int. Cl. D26—05

U.S. Cl. D48—23 R

FIG. 1 is a front view of a ceiling lamp, showing my new design;

FIG. 2 is a side view of the ceiling lamp as shown in FIG. 1;

FIG. 3 is a top view of the ceiling lamp according to the present design; and

FIG. 4 is a view from below of the ceiling lamp according to the present design.

The ceiling is shown in broken lines for illustrative purposes only.

I claim:

The ornamental design for a ceiling lamp, as shown and described.
